LIGHT FIXTURE CAP

Dillard M. Smith, Beverly Hills, and Jan Jaspers Fayer, Palos Verdes Peninsula, Calif., assignors to Eagle
Manufacturing Co., City of Industry, Calif., a corporation of California

Filed Sept. 15, 1965, Ser. No. 86,999

Term of patent 14 years

(Cl. D48—7)

The figure is a perspective view of a light fixture cap showing our new design.

The pattern of surface ornamentation in the single figure has been fragmentarily shown for convenience of illustration and is understood to be continuous about the cap.

We claim:

The ornamental design for a light fixture cap, substantially as shown and described.
